NAILMAKING MACHINE

José M. Bolaño, Buenos Aires, Argentina

Continuation of application Serial No. 40,735, July
26, 1948. This application July 12, 1951, Serial
No. 236,301

10 Claims. (Cl. 1—27)

1

The present invention relates to nail making machines and is a continuation of my copending U. S. patent application Ser. No. 40,735 filed July 26, 1948.

More specifically, the present invention relates to a nailmaking machine of the type which forms nails from sheet metal blanks, which shall furthermore be adapted during the same working cycle to drive the nails fabricated thereby into a workpiece, the double function being performed once for every full cycle of operation of the main working parts.

A number of nailing machines are known having various operating systems, in all of which, however, nails made outside the machine have to be fed thereto.

According to the present invention, the nailmaking and naildriving operations can both be performed by the one machine, due to the use of sheet metal blanks, which require only forming or pressing in order to produce finished nails, and, by reason of the fact that they are blanks, that is to say, small, flat metal plates, may be conveniently and compactly stored in the machine itself.

The advantages of the machine of the present invention may be compared to those of a stapling machine of the so-called sewing type, in which the staples are formed and applied, as and when required, from wire fed to the forming and stapling means from a supply coil.

It is, therefore, a principal object of the present invention to provide a nailmaking machine adapted to drive into a workpiece the nails made thereby.

A further object is to provide a machine of the type described including a reciprocating hammer member and a reciprocating slide structure comprising a plurality of cam actuated blank feeding and nail forming members.

A further object is to provide a nail making machine of the type described including a reciprocable slide structure comprising a magazine for nail blanks and a toggle actuated nail-forming ram means cooperating with a nail-forming groove and a relatively stationary head forming member to completely form a nail from a nail blank in one operation.

These and other objects and advantages of the present invention will become apparent in the course of the following detailed description of certain preferred embodiments thereof illustrated in the accompanying drawings, in which:

Fig. 1 is a general perspective view, of one embodiment of a combined nailmaking and nailing

2

machine of the present invention with certain parts broken away to show internal construction.

Fig. 2 is a perspective view of an end cover plate for a crosshead chamber forming part of the machine.

Fig. 3 is a perspective view of a slide structure and guide block in assembled relationship with certain parts broken away and showing the working parts in their lowermost position.

Fig. 4 is a perspective view of a cam groove member showing the inside face thereof, said cam groove member forming part of the guide block shown in Fig. 3 and being adapted to govern the operation of a nail-forming member.

Fig. 5 is a perspective view of a second cam groove member showing the inside face thereof, said second cam groove member also forming part of the guide block of Fig. 3 and being adapted to govern the operation of a head forming instrumentality mounted in said guide block.

Fig. 6 is a perspective view of the slide and guide assembly showing the rear face of the guide block with certain parts broken away to illustrate the cam for actuating the feed bar to place a blank in position to be formed into a nail.

Fig. 7 is a perspective view of a portion of the reciprocating slide structure with certain parts broken away.

Fig. 8 is a side elevation of a detachable accessory part of the reciprocable slide structure illustrating the guide construction for the heading member shown in Fig. 10.

Fig. 9 is an end view of the member shown in Figure 8.

Fig. 10 is a perspective view of a heading member.

Fig. 11 is a perspective view of a guide plate to be mounted in the slide structure for guiding the heading member, as shown in Fig. 18.

Fig. 12 is a perspective view of a stop plate to be mounted in the slide structure for limiting the inward stroke of the heading member, as shown in Fig. 18.

Fig. 13 is a perspective view of a feeder block which is also an accessory part of the reciprocable slide structure.

Figs. 14 and 15 are elevations of opposite sides of the feeder block of Figure 13.

Fig. 16 is a perspective view of the assembled reciprocable slide structure.

Fig. 17 is a cross-section of the guide block and slide structure in assembled relationship the plane of section being indicated at XVII—XVII in Figure 16, and being taken parallel to the bottom face of the reciprocable slide structure.

3

Fig. 18 is a cross-section similar to that of Fig. 17 but with reference to the plane XVIII—XVIII of Figure 16, also taken parallel to the bottom face of the reciprocable slide structure.

Fig. 19 is a side view of a hammer bar forming part of the machine.

Fig. 20 is an edge-on view of the hammer bar of Figure 19.

Fig. 21 is a front elevation of the cross-head chamber, reciprocable slide member and guide block assembly with certain parts broken away, the working parts being shown in their lowermost position.

Fig. 22 is a fragmentary view showing the guide block in section and the reciprocable slide structure partly in section, the working parts being illustrated in their uppermost position, the view being otherwise similar to the lower portion of Figure 21.

Fig. 23 is a section on the line XXIII—XXIII 20 of Figure 21.

Fig. 24 is a fragmentary sectional view similar to the lower portion of Figure 23 but with the working parts shown somewhat raised from their lowermost position.

Fig. 25 is a section similar to Figure 23 but with the working parts shown in their uppermost position.

Fig. 26 is an elevation of a nail blank for use in my novel machine, and

Figs. 27 and 28 are perspective views of a partly formed nail and a fully formed headed nail respectively.

As shown in Figure 1, the machine of the present invention comprises a pedestal 1, including an upper housing 2, in which the shafts 5 and 9 forming part of the actuating means for the machine are enclosed, and a table 3, adjustable as to height, as by means of hand-wheel 4 and adapted to support the work-pieces to be nailed together (not shown).

As will readily be appreciated in the course of the following description, the precise form and construction of the pedestal 1 and the manner of mounting the actuating shafts and the actuated instrumentalities thereon is of little importance as regards the present invention and the pedestal and method of mounting illustrated and described are merely illustrative.

The actuating means comprises a main shaft 5 adapted to be powered as by means of a pulley 6, intended to be driven in the usual way by belting (not shown) from a suitable source of power, said main shaft 5 being positively coupled as by gears 7 and 8 to a counter-shaft 9.

The end of the shaft 5 remote from the pulley 6 extends through a front wall 10 of the upper housing 2. Detachably positioned against said front wall 10 is a cross-head chamber 11, said chamber being detachably secured to said upper housing 2, as by screws 10a passing through a flange 10b surrounding said front wall 10. Chamber 11 is open at both its ends and, at the end opposite the wall 10, there is provided a detachable cover plate 12 adapted to be removably secured to said chamber as by means of screws 13, only a fragment of said cover plate being shown in Figure 1. The entire cover plate is best seen in Figures 2, 23 and 25, which show that the cover plate comprises a body portion 14, from one face of which projects a raised marginal portion 15, having plain holes 16 therein to admit of the passage of said fixing screws 13.

Returning now to Figure 1, the open end of the chamber has a flat margin 17, adapted to

be engaged by said raised marginal portion 15 of the cover plate, and said margin 17 is provided with drilled and tapped holes 18 adapted to receive said fixing screws 13.

The chamber 11 is defined by a peripheral wall 19 extending around the bottom and two sides of said chamber, the inner face of which is stepped as shown at 20 (see also Figs. 21 and 23) to provide an upper, wider compartment 21 and a lower, somewhat narrower compartment 22. The aforesaid end of the main shaft 5 extends into said upper compartment, and has fast on it a crank member 23, comprising a crank plate 24, from which projects a crank pin 25.

Similarly, the end of counter-shaft 9 remote from the gear 8 extends through the wall 10 into the lower compartment 22 of the chamber 11, and has fast thereon a platelike crank body 26, of a secondary crank 27 comprising a crank pin 28 projecting from said crank body.

The opposite vertical portions of the peripheral wall 19 of the chamber 11 are recessed on their inner faces to provide a pair of upper slideways, 29, 29a, (see Fig. 21), only one of which is shown at 29 in Figure 1, and a pair of lower slideways 30, 31, best seen in Figure 21, one of which, 30, can also be seen in Figure 1. It will be understood that the upper slideways are in the wall portions corresponding to the upper compartment 21 and the lower slideways are in the wall portions corresponding to the lower compartment 22.

An upper cross-head 32 is disposed in the upper compartment 21 with opposite ends slidably engaging the upper slideway 29 and the complementary slideway 29a therefor (see Fig. 21), so that upper cross-head 32 is adapted to slide up and down in said upper compartment, and to be actuated for such sliding motion by the upper crank pin 25 which extends into an elongated slot 33, provided in the upper cross-head 32 and disposed transversely of the upper compartment 21.

Depending centrally from the lower portion of the upper cross-head 32 is a hammer bar 34 which extends downwardly through the lower compartment 32 into a reciprocable slide member 35 in a manner and for a purpose to be hereinafter explained. In Figure 1 the hammer bar 34 is shown broken so as to expose the lower crank pin 28.

In the lower compartment 22 of the chamber 11 there is similarly located a lower cross-head 36 having a slot 37 into which lower crank-pin 28 extends, opposite ends of said lower cross-head being slidably disposed in the slideways 30 and 31. Said lower cross-head 36 forms a part of said slide structure 35 which is adapted to extend into the lower compartment 22, through an opening 38 provided in the lower wall 39 of the chamber 11, whereby the upper portion of the slide structure 35 is adapted to be raised into said lower compartment 22 when the lower cross-head 36 moves upwardly in the slideways 30 and 31 as will be hereinafter explained.

The lower cross-head 36, crank 27 and counter shaft 9 thus form actuating means for the slide structure 35, and the upper cross-head 32, crank member 27 and shaft 5 form separate actuating means for the hammer means 34 to reciprocate the same in timed relationship with the reciprocation of the slide structure 35.

The lower portion of the slide structure 35 is adapted to reciprocate in a guide block indicated by the general reference numeral 42 which

is also detachably secured to the housing 2 of the pedestal 1. To this end the flanges 10b surrounding the end wall 10 have downwardly directed extensions 40 which, as seen at 41 in Figs. 23, 24 and 25, are offset to the rear, that is towards the pulley 6, to allow for the greater width of the guide block.

As indicated in Figure 1 both the chamber 11 and the guide block 42 are conveniently secured to the flanges 10b and 40 of the housing 2 as by means of fixing screws some of which are shown at 10a and 43 passed through said flanges from the side thereof nearest to the pulley 6 and thus screwed into the back of chamber 11 and guide block 42.

From the foregoing description it will have been noted that the upper compartment 21 is defined only by the corresponding portions of the wall 19 which extend only along opposite sides of said compartment, and of course, when the chamber 11 is assembled to the upper housing 2, also by the front wall 10 and the cover plate 12, so that as so far described said upper compartment is open at the top. The top of the compartment 21 which is also the top of the chamber 11 is covered over by a detachable top plate 44 which may be secured in position to bridge opposite side portions of the wall 19, as by screws 45. The reason for this construction is to enable the upper cross-head 32 to be inserted into the slideways 29, 29a when assembling the parts. It is preferred to assemble first the reciprocable slide structure 35, except for certain accessories as will hereinafter appear, then to assemble said slide structure with the guide block 42, and thereupon to introduce the upper portion of the slide structure 35, including of course the lower cross-head 36, into the chamber 11 through the lower opening 38. If the hammer bar 34 is detachably mounted to the upper cross-head 32, as will hereinafter be explained, said hammer bar may be introduced into said chamber 11 through the bottom together with the upper portion of reciprocable slide structure 35. Supposing the top plate 44 to have been removed from the wall 19, the upper cross-head 32 may be inserted from above into the slideways 29, 29a, and, if necessary, coupled to the hammer bar 34. The top plate 44 is then secured in position and the whole of this assembly comprising the chamber 11, cross-heads 32, and 36, reciprocable slide structure 35 and guide block 42, may, after fitting of any previously omitted accessories, be secured to the flanges 10b and 40 of the upper housing 2, during which operation the crank pins 25 and 28 may readily be inserted into the corresponding slots 33 and 37. Whereupon the coverplate 12 may be secured to the front of chamber 11.

Referring now to Figures 3, 4 and 5, the guide block 42 comprises a main channel shape body member 46 secured, as hereinabove described, to the upper housing 2 so that the open side of the central channel 47 is free. The width of said channel 47 is such as to allow the lower portion of the slide structure 35 to slide freely therein, but the depth of the channel 47 is less than the thickness of said slide structure so that the latter projects beyond the end faces 48 and 49 of the legs 50 and 51 respectively of said body member 46. The difference between the depth of the channel 47 and the thickness of the lower portion of the slide structure 35 is taken up or compensated by two bridge members 52 and 53, which are interposed respectively between the legs 50 and 51 and a retaining plate 54, which retaining plate extends the full width and height of

the body member 46 as is seen in Fig. 1. The assembly composed of the parts 46, 52, 53, and 54 is secured together as a guide block as by means of screws 55 passing through the retaining plate and through holes, such as the holes 56; in the bridge members and engaging internally threaded holes, such as the holes 57, in the end faces 48 and 49 of the legs 50 and 51.

Turning now more particularly to Figures 4 and 5, the bridge members 52 and 53 are of a generally similar structure and comprise a recess, in the bottom wall of which a cam groove is provided. However, the recess 58 of the bridge member 52 is relatively long and deep and defines two relatively narrow legs 59 and 60 of which the latter is the narrower, said legs being located at the extreme ends of bridge member 52. The cam groove 61 at the bottom of the recess 58 of bridge member 52 comprises a lower straight portion 62, an upper straight portion 63 offset with respect to said lower portion but parallel thereto, and one intermediate inclined operative portion 64. As seen in Figure 4 said lower portion 62 of the cam groove 61 is offset to the left of the upper portion 63, but it will be appreciated that when the bridge member 52 is in an assembled position said lower portion 62 will lie on the side of the centre line of said upper portion 63 remote from the slide structure 35. Since the parts are to be regarded in their assembled relationship, locations remote from the slide structure 35 (such as that of said lower portion 62 of the cam groove 61), will be hereinafter referred to as "outward locations," and movements away from the slide structure will be referred to as "outward movements." Similarly, locations nearer to the slide structure 35 and motions towards the latter will hereinafter be referred to as inward locations and inward motions respectively. These terms "outward" and "inward" will be employed in the same sense with respect to all sides of the slide structure 35, so that outward motion (or position) referred to one side will be in the opposite direction or perpendicular to, outward motion referred to another side, and similarly for the inward motion (and positions).

The bridge member 53 seen in Figure 5 comprises a relatively shallow recess 66 defining an upper relatively narrow foot 67 and a lower relatively long bearing portion 68. In the bottom of the recess 66 is a cam groove 69 comprising a lower outwardly located straight arm 70, parallel to the longitudinal centre line of bridge member 53 and an intermediate inwardly inclined arm 71 and an upper arm 72 parallel to the lower arm 70 and offset inwardly of the latter.

As seen in Figures 3, 21 and 22, in the end face 48 of the leg 50 of the channel shape body member 46, to which end face the bridge member 52 (Fig. 4) is adapted to be applied, there is provided a contoured recess 73 defined by a peripheral guide wall 74, which, on the inward side of the recess, comprises a straight portion 75 parallel to the longitudinal center line of said end face 48, and on the outward side includes lower and upper straight end portions 76 and 77 respectively, best seen in Figures 21 and 22, which are parallel to the straight portion 75 and are connected by an outwardly arcuate intermediate portion 78. The outward and inward portions of the peripheral wall 74 are connected together by lower and upper arcuate end portions 79 and 80.

Secured to the outside of the aforesaid leg 50 and in a position to cooperate with the guide wall 74 as will hereinafter be explained, is a cam strip

81 comprising an inwardly lying straight member **82** parallel to the straight portion **75** of the guide wall **74** and located in close proximity to the side face **83** of said leg **50**. The cam strip **81** further comprises an outward member **84** the shape of which is generally similar to the contour of the outwardly lying portion of the guide wall **74**, so that said outward member comprises lower and upper straight segments **85** and **86** connected together by an outwardly arcuate intermediate segment **87**, and an inclined resilient end guide segment **85a**, the free end of which normally rests against the outer face **83** of the leg **50**. The total length of the cam strip **81**, that is the overall distance from the free end of the end guide segment **85a** to the opposite end of the upper segment **86**, is slightly less than the overall length of the contoured recess **73**, that is to say, than the distance between the lower and upper end portions **79** and **80** thereof, for a purpose which will become apparent hereinbelow. As shown in Figure 3 the cam strip **81** may be secured to and spaced from the outer face **83** of the leg **50** by means of an attachment strip **88** and screws **89**, and conveniently the straight member **82** may be integral with said attachment strip and extend laterally therefrom.

The guide block considered as a whole, has therefore a slot, hereinafter called heading slot, in one side and an elongated opening in the opposite side, said slot and opening being defined in the embodiment shown by the respective recesses **66** and **58** of bridge members **53** and **52**, and the part of the end faces of the respective legs **51** and **50** bridged thereby. As will afterwards appear there is a further slot to be called magazine slot in the same side of the guide block as the heading slot, and a feeder slot in the rear wall of the guide block as now about to be described.

As seen in Figures 6, 17, 23, 24 and 25, the rear wall **90** of the channel shape body member **46** has a slot **91** formed therein and extending therethrough, said slot being substantially centrally disposed in said rear wall **90** and extending as regards its major dimension parallel to the longitudinal center line of said body member **46**. Said slot **91** is adapted to receive complementary blocks **91a** and **91b** having each a countersunk side face **92a** and **92b** (see Figs. 6 and 17). As best seen in Figs. 6, 23, 24 and 25, in at least one of said side faces, for example the side face **92a**, there is provided a bifurcated cam groove **93**, having an upper straight trunk portion **94** which is in alignment with a lower straight branch **95**, and an arcuate branch **96**, extending from an inwardly inclined transfer branch **96a**, inwardly and upwardly to join the trunk portion **94**, said transfer branch extending from the lower end of the arcuate branch **96** outwardly and upwardly to meet the lower end of the lower straight branch **95**. The trunk **94** and straight branch **95** of the bifurcated cam groove are disposed parallel to the longitudinal center line of the side face **92a**. The arcuate branch **96** is so arranged that it extends from the trunk **94** and straight branch **95** towards the open side of body member **46**. It will be understood that the straight and arcuate branches **95** and **96** of the cam groove **93** define between them an island portion **92c**.

The complementary blocks **91a** and **91b** are adapted to be removably secured in position in the slot **91** as by means of screws **97**, and define between them a feeder slot **91c**.

With reference in general to the cam grooves and contoured recess and the like, hereinabove

described, it should be pointed out that, although the general features thereof must be substantially as described, the actual design or proportion of the constituent parts and hence, the final appearance and dimensions of such grooves and recesses, will depend to a certain extent on the size and relative proportions of the other component parts of the mechanism and also upon the size of the nail to be manufactured by the machine. It will also be appreciated that the exact position of such grooves and recess in the respective machine parts, with regard for instance to their disposal about the center lines of such parts, will also to some extent depend upon the factors just mentioned. Hence, the relative locations and dimensions of such cam grooves and recesses shown in the accompanying drawings are to be taken as being merely illustrative except for the essential characteristics mentioned hereinabove, such as comprising straight portions joined by inclined or arcuate portions. Moreover, for the purpose of more clearly representing such cam grooves and recesses as well as the guide strip **81** some dimensions have been purposely exaggerated in the drawings. It is thought, however, that this specification contains sufficient information to enable anyone skilled in the art to design practical embodiments without any difficulty.

30 As can be seen in Figs. 6 and 17, the other leg **51** of the body member **46** has an elongated slot **98** extending heightwise of the body member and parallel to the longitudinal center line thereof, said slot being adapted to receive a magazine member to be described hereinbelow for heightwise reciprocation in said slot.

35 Turning now to Figs. 6, 7, 16, 17, 23, it will be noted that the reciprocable slide structure **35** comprises a plunger body **99** having a substantially L shape cross section. Said plunger body has an upper end **100**, a rear face including an upper portion **101** and a lower portion **101a**, a narrow side face **102**, a wide side face **103** and a front face comprising an inwardly offset portion **104** and a front portion **105**, between and perpendicular to which, is a transverse face **106** defining one side of a hammer guide channel **107**, the outer end **108** of which (that is the end nearest the front portion **105**) is defined by a shoulder or step **109** projecting from the front portion **105**, whereas the inner end **110** of said hammer guide channel **107** is defined by a step **111** formed in the offset portion.

40 That part of the plunger body defined by the front portion **105** and wide side face **103** may be regarded as the long leg of the L and it extends below the short leg of the L defined by the offset portion **104** and the narrow side face **102**. Said short leg has a bottom face **112** on which are provided centering pins **113**, and which has a drilled and tapped hole **114** to receive a fixing screw for securing a complementary part to said bottom face. Said complementary part will be more particularly described hereinbelow with reference to Figs. 13, 14 and 15. As best seen in Fig. 7, near its lower end the front portion **105** of said longer leg is cut back to form a pair of spaced steps **115**, the front faces **116** of which lie in the same plane at a level below said front portion **105** and are provided with screw holes **117** so as to have secured to them a cover plate **118**. The parallel faces **119** of the steps **115**, that is to say, the faces which are perpendicular to the front portion **105** define together with the inner face **120** which connects said parallel faces, a

press channel 121 adapted to be covered by the cover plate 118 and to be open transversely of said longer leg.

The difference in level between the inwardly offset portion 104 and the front portion 105 of the plunger body 99 is adapted to be compensated by compensation plate 122, best seen in Figs. 8, 9 and 16. Said plate has a narrow grooved face 123, which is adapted to engage the edge of the shoulder 109, and an inner face 124 adapted to engage the inwardly offset portion 104 and to extend therebeyond for the same distance as the lower part of the longer leg of the plunger body. In order to secure accurate fitting of the compensating plate in the plunger body, dowel members, such as those shown at 125 in Figs. 8 and 9, may be provided on the compensating plate and corresponding dowel holes 126 may be provided in the inwardly offset face 104 (see Fig. 7). It is to be understood of course instead of providing dowels exclusively on the plate 122 and dowel holes in the face 104, I may provide some dowels and some holes on and in each of these two members. The compensating plate 122 may be detachably secured to the inwardly offset face 104 as by countersunk screws 127 (see Figure 16) passing through holes 128 in plate 122 and into tapped holes 129 in the face 104.

Extending lengthwise of the narrow grooved face 123 (Figs. 8, 16 and 17) is a narrow and shallow groove 130. As shown, said groove is slightly offset towards the inner face 124 of the compensating plate 122. At a position in the neighbourhood of the lower end of said compensating plate 122 to be determined by the relative locations of other parts to be hereinafter described, I provide a stepped recess extending transversely of the compensating plate and comprising a narrow shallow groove 131 extending from the outer side face 132 of plate 122 to the groove 130. Said stepped recess further comprises a heading member guide channel 133 of substantial width and a pair of spaced bearing surfaces 134 extending widthwise away from said guide channel and adapted to be engaged by flanges 135 of a main closure plate 136 and an auxiliary check plate 137 (see Figs. 10, 11 and 12). The check plate 137 is adapted to be positioned on the bearing surfaces 134 at the ends thereof nearer the longitudinal groove 130 of the compensating plate 122 and said check plate is preferably of uniform cross-section. The main closure plate 136 has a bearing face 138, parts of which are adapted to engage the bearing surfaces 134 and has furthermore a substantially centrally disposed recess 139 which, in the assembled position of closure plate 136, extends parallel to the transverse groove 131. The plates 136 and 137 are adapted to be detachably secured in position on the bearing surfaces 134 as by means of screws 140 (see Fig. 21), to which end plain countersunk holes 140a are provided in the plates 136 and 137 and tapped holes 140b in shoulders 134 of plate 122. In the heading member guide channel 133 a heading member 141 (see Figs. 10, 16, 21 and 22) is adapted to fit slidably, said heading member having on one side thereof a substantially centrally disposed raised or thickened portion 142 extending lengthwise of said heading member and adapted to engage the central recess 139 of the closure plate 136. On either side of said thickened portion of the heading member 141 are somewhat thinner flanges 143 adapted to fit in the upper and lower narrower

portions of the heading member guide channel 133. On the side of the heading member remote from the thickened portion 142 I provide a heading finger 144 disposed parallel to the longitudinal center line of the heading member and as shown to one side of said center line, said heading finger 144 projecting beyond one end 145 hereinafter called the "inward end" of the heading member. Said heading finger 144 is adapted to be a sliding fit in the transverse groove 131. On the same side as the heading finger 144 but adjacent the other, outward end of the heading member 141, is a cam follower pin 146 which is there provided for a purpose to be hereinafter explained. It should be understood that the overall length of the heading member is such that in the assembled condition the end thereof remote from the front face 145 projects beyond the outer face 132 of the compensating plate 122, Figs. 8 and 9.

Turning now to Figs. 7, 13, 14, 15 and 16 it will be seen that the plunger body 99 as so far described still has, even after the application of the compensating plate 122, an unfilled gap 25 extending inwardly from the lower portion 101a of the rear face of the plunger body and defined by the bottom face 112 of the shorter leg and the uncovered portion of the lateral face 147 of the lower end of the longer leg of the plunger body. To fill this gap in the manner indicated in Fig. 16, I provide a feeder block 148, the general shape of which is such as to fill said gap so as to complete the rectangular cross-section which the slide structure 35 has near the lower end thereof. Said feeder block 148 has an upper face 149 drilled as indicated at 150 to receive the positioning pins 113 and further drilled to provide a hole 151 extending heightwise right through said feeder block to permit of the insertion of a fixing screw 152. The feeder block 148 also has an inner side face 153 adapted to engage the lateral face 147 of the plunger body and recessed transversely of the feeder block to provide a feed bar channel 154 and shoulders 155 to which guide plates 156 may be secured, as by means of screws 157 to retain in the feed bar channel a slidably feed bar as will hereinafter be described.

The feeder block further has an inside face 158 adapted to engage the inner face 124 of the compensating plate 122, and an outside face 159, which in combination with the narrow side face 102 of the plunger body 99 helps to complete the contour of the sliding member 35. Formed in the inside face 158 and extending right across the feeder block 148 so as to communicate with the feed bar channel 154 and to appear in the outside face 159 is a magazine channel 160 which is laterally closed or completed by the engagement of the inside face 158 of the feeder block 148 with the inner face 124 of the compensating plate 122.

Turning now to other accessories to be fitted into the slide structure 35 and referring more particularly to Figs. 3, 16, 17 and 21, I provide a magazine housing 161 adapted to fit in the magazine channel 160 of feed block 148 (Fig. 14) and to extend into said channel so that the inner end of the magazine housing is flush with the side of the feed bar channel 154 (Figs. 13 and 17). The magazine housing 161 extends outwardly beyond the outside face 159 of the feeder block 148 a sufficient distance to pass through the magazine slot 98 to the outside of the corresponding leg 51 of the channel shape body mem-

ber 46 when all the parts are in assembled condition and to extend slightly beyond the outward face 162 of said leg 51 of the channel shape body member 46. At the outside end of the magazine housing I provide closure means such as the cover slide 163 (see Fig. 17) which is adapted to fit in channeled flanges 164 provided at said outer end of the magazine housing. Within said housing I provide also a feeding spring 165 extending between said cover slide 163 and the outermost one of a plurality of nail blanks 166 contained in said magazine housing. On the same side of the sliding member 35 as the one from which the magazine housing 161 projects I provide the heading member 141 which, as can be seen in Figs. 16 and 18 extends beyond the outer side face 132 of the compensating plate 122, and, in the assembled condition of the parts said heading member extends into the heading slot defined by the shallow recess 66 (Fig. 5) of the bridge member 53 pertaining to the guide block, the cam follower pin 146 of the heading member 141 engaging the cam groove 69 in said shallow recess 66.

As seen in Figs. 3 and 7, the inner end of the magazine housing 161 lies flush not only with the side of the feed bar channel 154 but also with the grooved face 123 of the compensating plate 122.

In the feed bar channel 154 which is perpendicular to the center line of the magazine housing, I provide a feed bar 167, one end of which, namely, the one which in the assembled condition of the parts is nearer the magazine housing is of reduced thickness to provide a feeder tongue 168. The feeder member 167, 168 has a face substantially coplanar with the inner end of the magazine housing and the open side of the groove 130, namely the face contacting the afore-mentioned side of the feed bar channel 154, and is thus adapted to reciprocate in front of and in close engagement with said inner end of the magazine housing 161 to feed a blank at a time towards a position in front of and in engagement with the grooved face 123 of compensating plate 122 in such a manner that the central longitudinal strip of the blank overlies the open side of longitudinal groove 130.

The opposite end of the feed bar 167 is provided with cam follower means such as the camming pin 169, for instance on the same side of the feed bar as the feeder tongue, said end of the feed bar, in the assembled condition of the parts, extending into the feeder slot defined by the cooperating counter-sunk side faces 92a and 92b of complementary blocks 91a and 91b pertaining to the guide block and so that the camming pin shall engage in the bifurcated cam groove 93.

On the side of slide structure 35 opposite the magazine and heading member, I provide a pressing assembly 170 including a channel shape ram guide 171 and a ram 172. As shown in the drawings (Figs. 3, 17, 21 and 22) the ram guide has projecting from one side of it, a guide pin 173, and on the opposite side, has a slot 174 through and beyond which an actuating pin 175 extends, said actuating pin being fast on said ram 172. In the arrangement shown, the guide pin 173 and the actuating pin 175 are so disposed on the pressing assembly that the guide pin will, in the assembled position of the parts, extend into the contoured recess 73 to engage the defining walls thereof and the actuating pin 175 will extend into the cam groove 61 of bridge member 52 (Fig. 4) which, it will be recalled, is applied to the leg 50

of the channel shape member 46. Furthermore, the pressing assembly is adapted to reciprocate in the press channel 121 provided in the lower portion of the plunger body, the arrangement being such that the ram 172 is aligned with the open side of longitudinal groove 130 in the compensating plate 122, and the ram and ram guide move perpendicularly to the common plane of the inner end of the magazine or open side of groove 130.

The ram 172 is an accurate sliding fit between the legs 176 of the channel shape ram guide 171 and is of a width substantially equal to the width of the longitudinal groove 130 less twice the thickness of a nail blank, so that the ram can cooperate with said groove to press a nail blank into the groove as will hereinafter be described to perform one step in the nailforming operations. Since the ram 172 is an accurate sliding fit in the ram guide 171, it follows that the end edges 177 of said ram guide (see Fig. 3), at the inward end thereof will overlap corresponding edges of the longitudinal groove to the extent of one thickness of a nail blank, so that if, after a blank has been forced by the ram 172 into the longitudinal groove 130 in such a manner that what were previously the longitudinal side edges of the flat nail blank are flush with the grooved face 123 of the compensating plate 122, the ram guide is advanced to engage said grooved face, said end edges 177 will act to hold the partly formed blank securely in said longitudinal groove even if the ram is retracted therefrom.

The ram guide 171 has secured to the outward end thereof a transversely disposed camming member 178 having upper and lower bevelled camming edges 179 and 180 respectively. The lower bevelled edge 180 is disposed on the outward side of the camming member 178 and is adapted to coact with the end guide segment 85a of the cam strip 84 secured to the leg 50 of the channel shape body member 46, to raise said guide segment 85a from the side face 83 of said leg 50 to permit the camming member 178 to pass between said end guide segment 85a and said face 83 at a certain point in the operation of the device. As will hereinafter be explained, said lower camming edge 180 is also adapted to coact with the upper end of the cam strip 81 to guide the camming member 178 into the space between the straight member 82 of the cam strip 81 and said side face 83, as will also be hereinafter made clear.

The upper bevelled camming edge 179 is disposed on the inward side of the camming member 178 and is adapted to cooperate with the outward face of the end guide segment 85a to assist in guiding the camming member 178 onto the outward face of the outward member 84.

Referring now to Figs. 19, 20 and 21, the slide member assembly further comprises a hammer bar 34 of cross-section such that it will be a good sliding fit in the guide channel 101. The upper end of said hammer bar, as has already been indicated, is secured to the upper cross-head 32.

As best seen in Figs. 21 and 23, for example, and as shown, the hammer bar 34 is detachably secured to a forwardly extending projection 32a provided on the lower edge of the upper cross-head 32 and so positioned that the hammer bar 34 when secured in place and when the whole of the operating parts are assembled, will be in strict alignment with groove 101 (Figs. 7 and 25).

The hammer bar 34 may be fixed to the projection 32a as by bolts 32b and nuts 32c.

At its other end and on one side of the hammer bar 34 I provide a hammer member 181 of cross-sec-

tion to be a good sliding fit in the longitudinal groove 130 of the compensating plate 122, and substantially of the same cross-sectional area.

As already indicated the lower cross-head 36 forms part of the reciprocable slide member 35 and to this end is preferably secured to or formed integrally with the upper end of the plunger body 99 and is located to the rear of said upper end so that in the assembled condition of the machine the hammer bar 34 may reciprocate in front of the lower cross-head 36 without fouling.

The machine, as so far described operates as follows, particular reference being had to Figs. 3, 17, 18 and 21 through 25. In Figs. 3, 21 and 23 the parts are shown in their lowermost position and in Fig. 3 I have shown the magazine housing 161 empty as if the machine were about to be used for the first time. It will be noted that with the parts in the position shown in Figs. 3 and 21, the hammer bar 34 is also in its lowest position with the hammer member 181 extending to the bottom of the groove 130 of compensating plate 122. The heading member 141 and the feeder tongue 163 are in the outward or retracted positions whereas the pressing assembly 170 is in its inward or advanced position, in which, however, the ram 172 is in retracted position with respect to the groove 130. The camming member 178 is just below the end guide segment 85a of the cam strip 81, with the upper bevelled camming edge 179 in engagement with the outer face of the lower end of the end guide 85a. For clarity it may be mentioned that the cam follower pin 146 of the heading member 141 and the actuating pin 175 of the ram 172 are, in the positions shown in Figs. 3 and 21, at the bottom of the lower arm 70 and the lower portion 62 respectively of the cam grooves 69 and 61 in bridge members 53 and 52. The guide pin 173 of the channel shape ram guide 171 is similarly at the bottom of the lower portion 76 of the contoured recess 73 and, as seen in Fig. 21, the camming pin 169 of the feed bar 167 (see Figs. 6 and 17) is at the lowest point of the bifurcated groove 93 (Fig. 23). This lowest point coincides with the juncture of the inclined branch 96a and the arcuate branch 96 so that the camming pin 169 is in a position to follow the arcuate branch 96 rather than the straight branch 95 when subsequently moved upwardly with respect to said bifurcated groove.

It will now be supposed that the magazine housing 161 is loaded with a charge of blanks and closed at its outer end with the spring 165 in position between the rearmost blank and the slide 163 as shown in Fig. 17. As soon as the charge is in position the innermost blank 166a (see Fig. 23) will be positioned opposite the inward end of the feeder tongue 166 (see also Fig. 17) and substantially in engagement therewith. It may here be remarked that the section of the lower portions of Figs. 23, 24 and 25 has been taken in the plane of the surface of the hammer bar 34 adjacent the inward end 123 of the compensating plate 122, which inward end 123 lies in a common plane of contact with said surface. The section of the lower portion of Figs. 21, 22, has been taken on a plane defined by the surface of the ram 172 remote from the end 48 of the leg 50 of the channel shape member 42 of the guide block assembly, which plane includes the corresponding surfaces of the hammer member 181 and the heading finger 144 except for the thickness of a nail blank, which thickness has however been neglected in taking the section. With the dimensions chosen, 75

this section plane also passes just to the outside of the cam follower pin 146 of the heading member 141 so that bridge member 53 is also in section in a plane coinciding with the bottom cam groove 69, but the section plane will extend between the bottom of recess 53 of the other bridge member 52 and the face 48 of the leg 50.

Referring now also to Fig. 1 and supposing that after loading of the magazine a work piece to be nailed has been placed on the table 3 below the guide block assembly 42, if the pulley 6 is caused to rotate, the main shaft 5 will be rotated and thereby, for the reasons already set forth, cause rotation of counter-shaft 9 and the crank member 23 and secondary crank 27. Rotation of crank member 23 will, by raising upper crosshead 32 retract the hammer bar 34 and hammer member 181 with respect to the reciprocable slide member 35 inasmuch as the throw of the crank member 23 is greater than the throw of the secondary crank 27, so that the upper crosshead 32 will be displaced upwardly and thereafter downwardly also, at a greater rate than the lower crosshead 36 and also to a greater extent. Hence, there will be relative movement between the reciprocable slide member 35 and the fixed guid block assembly 42 by reason of the motion of the lower crosshead 36 and also relative motion of the hammer bar and hammer member with respect to the reciprocable slide member 35.

During the upward motion of the upper crosshead 32, therefore, the hammer member 181 will be retracted in the groove 130 (Figs. 3 and 21) and the parts are so proportioned that when the crank member 23, and, therefore, also the upper crosshead 32, has reached the top of its stroke, the hammer member 181 will have been retracted upwardly for a distance equal to at least the full height of a nail blank.

At this juncture and with reference to Figs. 26 through 28, it may be explained that the nail blanks 166 I use are in general of a rectangular shape having, a lower pointed end 182 and at their upper end a projecting appendage 183 lying in the general plane of the blank and disposed centrally of its widthwise dimension, said appendage being intended to provide a head after being bent over as will hereinafter be described. The width of the appendage 183 is such that it will fit into the longitudinal groove 130 of the compensating plate 122 and the inclined edges 183a forming the pointed end 182 are long enough to extend into marginal portions 184 of the blank which marginal portions themselves extend lengthwise of the blank on either side of a central strip 185 of width to fit into said longitudinal groove 130. Hence the full length of the nail blank is from the extreme end of the point 182 to the extreme end of the appendage 183.

Continuing now with the description of the operation of the machine, and with reference to Figs. 21 through 25, it will be observed that, inasmuch as the face of the hammer member 181 which is exposed when said hammer member is in groove 130, is flush with the inward end face 123 of the compensating plate 122, the presence of the hammer member 181 in the lower portion of the groove 130 will not affect the positioning against said inward end face 123, of a nail blank, and it is required that the hammer member 181 be in fully retracted position only when the ram 172 is about to be urged forward to perform a nail pressing operation.

Considering now more particularly the lower

cross-head 36 which is connected to or forms part of the reciprocable slide member 35, it will be noted (Figs. 22 and 24) that upward movement of lower crosshead 36 will cause upward movement of the slide member 35 to displace the cam follower pin 146, the camming pin 169 and the guide pin 173 and the actuating pin 175 in their respective cam grooves, bifurcated groove and contoured recess to actuate the associated parts. Owing to the hereinbefore described shape of the grooves and recesses, during the first part of the upward travel of the slide member 35, the cam follower pin 146 and the actuating pin 175 will move only upwardly along the lower portions 70 and 62 respectively of cam grooves 69 and 61 so that there will be no inward or outward displacement of either the heading member 141 or the ram 172. The channel shape ram guide 171 will almost immediately begin to move outwardly by reason of the engagement of the upper bevelled camming edge 179 of the camming member 178 with the inclined end guide 85a to bring the guide pin 173 into engagement with the lower straight portion 76 of the outward lying part of the guide wall 74 of the contoured recess 73. The ram guide 171 will therefore be retracted with respect to the longitudinal groove 130 and the inward end face 123 of compensating plate 122, to permit the passage into position in front of said groove of a nail blank.

At the commencement of the upward motion of the slide member 35 and with reference to Fig. 23, the feed bar 167 and feed tongue 168 are in such a position, slightly advanced inwardly from their outermost position (in which the camming pin 169 is in engagement with the straight portions 95, 94 of the bifurcated groove 93) that the inward edge 186 of the feeder tongue 168 just engages the outer edge of a nail blank 166a which has been fed forward by the action of spring 165 (see Fig. 17) against the lateral face 141 of the lower portion of the plunger body 99. In Figs. 23, 24 and 25 the plane of section passes just in front of the inward end of the magazine housing 161 so that the nail blank 166a engaged by the inward edge 186 of the feeder tongue 168 is visible. Since the camming pin 169 is, as hereinabove explained, in a position, at the very commencement of the upward movement, such that it will follow the arcuate branch 96 of the bifurcated groove 93, upward movement of the reciprocable slide 35 will cause inward movement of camming pin 169 to move the feed member 167 inwardly to push the nail blank 166a towards the longitudinal groove 130, that is to say towards a position in which the central strip of said nail blank 166a is in alignment with the inward end of the ram 172. This final position is shown in Fig. 24.

Continued upward motion of the reciprocable slide 35, will bring the actuating pin 175 of the ram 172 (see Figs. 3, 4 and 5) into the inwardly inclined portion 64 of the cam groove 61 and also brings cam follower pin 146 of the heading member 141 into the inwardly inclined portion 71 of the cam groove 69 and causes the guide pin 173 of the ram guide 171 to approach the arcuate portion 78 of the contoured recess 73. Said guide pin 173 is held in engagement with the outwardly lying wall portion of the contoured recess 73 by the action of the camming member 178 as it rides over the outer face of the cam strip 81.

Movement of the actuating pin 175 and the cam follower pin 146 in the inclined portions

of their respective cam slots, causes the ram 172 and the heading member 141 to be advanced inwardly so that the inward ends thereof approach from opposite sides the longitudinal groove 130, the heading finger 144 of the heading member 141 moving along the transverse groove 131 as can readily be appreciated from an inspection of Fig. 3.

The parts are so proportioned that when the inward edge of the ram 172 is about to engage the central strip of the nail blank positioned as already described, the camming member 178 will commence to move over the arcuate segment 87 of the camming strip 81 so that the guide pin 173 will commence to move along the arcuate portion 78 of the contoured recess 73 to retract the ram guide 171 from the nail blank.

It is to be understood that when the feeder tongue 168 feeds the strip 166a into position in front of the groove 130, the ram guide 171 has been retracted by the action of the end guide segment 85a just sufficiently to allow said nail blank to pass between the inward end of the ram guide and the inner end face 123 of the compensating plate 122, so that the ram guide 171 will act until retracted, to maintain the nail blank 166a against inner face 123. It will also be appreciated, particularly from Figs. 7 and 17, that outward movement of the nail blank 166a beyond the groove 130 is limited by the overlap of the inner end of the cover plate 118 beyond the lateral face 141 to the extent of bringing said inward end to the same level as the step 111 and the shoulder 109.

During the aforesaid continued upward movement of the reciprocable slide 35, the camming pin 169 of the feeder member 167 will move in the outwardly directed part of the arcuate branch 96 of bifurcated groove 93 (compare Figs. 23, 24 and 25) to cause retraction of said feed member from the nail blank 166a and to thereby gradually uncover the inward end of the magazine housing 161.

As the reciprocable slide 35 further continues its upward motion, the ram 172 will be advanced by movement of the actuating pin 175 in the inclined portion 64 of cam groove 61 (Fig. 4) to force the central strip of the nail blank 166a into the longitudinal groove 130 (Fig. 22) whereby the lateral margins of said blank are bent away from the inner face 123 of compensating plate 122 and towards the ram guide 171, which, during this part of the operation, is rapidly moved by the arcuate segment 87 of camming strip 81 and arcuate portion 78 of contoured recess 73 respectively, to its outermost or fully retracted position, so as to allow said lateral margins of the nail blank to be bent up as described.

Comparing Figs. 4 and 5, it will be noted that the upper straight portion 63 of the cam groove 61 is longer than the upper straight portion 72 of the cam groove 69, so that the ram 172, the actuating pin 175 of which travels in the cam groove 61, will reach its inmost or extreme advanced position in which it completes the first of the two nail forming steps, before the inner end of the heading finger 144 of the heading member 141 (the cam follower pin 146 of which travels in the groove 69) reaches its inmost or head forming position. It will also be noted that because of this timing relationship, the ram 172 (Fig. 22) will remain in its fully advanced position while the heading finger 144 moves into and out of its respective fully

advanced position, whereby the upper end of the ram 172 acts as an anvil over which the appendage 183 of the nail blank may be bent by the heading finger 144. This second and final nail forming operation, namely the bending over of said appendage to form a nail head, is effected as the ram and heading finger 144 reach their uppermost positions (see Fig. 22).

During the first and second nail forming steps, the feeder member 167 will have been moved by engagement of its camming pin 169 with the trunk portion 94 of the bifurcated groove 93, into its outermost or fully retracted position as shown in Fig. 25 so as to clear the inner end of the magazine housing 161, and thereby allow another nail blank 166b to be advanced by the spring 165 against the lateral face 147 of the plunger body 99, in position to be moved opposite the longitudinal groove 130 at the commencement of the next cycle of operations.

It will be appreciated that when the various cam follower and actuating pins have reached their uppermost positions the reciprocable slide 35 and also the crossheads 36 and 32 will have reached their uppermost positions, so that at the same time the hammer bar 34 will likewise have been raised to bring the hammer member 181 into fully retracted position, in which its lower end, as indicated in Fig. 22, is just above the inward end of the heading finger 144 when the latter is in fully advanced position.

With the parts in the mutual relationship just described, they are ready to commence the downward or return stroke. Continued rotation of the main shaft 5 will therefore initiate the return stroke during which the cam follower pin 146 of the heading member 141 will move downwardly in cam groove 72 and 76 from the position shown in Fig. 22 to the position shown in Fig. 23 and the actuating pin 175 of the ram 172 will move downwardly in cam groove 61 to be eventually retracted into their outermost positions, from the position shown in Fig. 3 to the position shown in Fig. 21, as will readily be understandable from the drawings.

The camming pin 169 (Fig. 25) of the feeder member 167 in moving down will follow the straight trunk 94 and the straight branch 95 of the bifurcated groove 93, thereby retaining the feeder member 167 in outermost or fully retracted position until, near the end of the downstroke the camming pin 169 engages the inwardly inclined branch 96a of the bifurcated groove 93 to move the feeder member 167 inwardly to bring the inward edge 166 of feeder tongue 168 into engagement with a new blank such as the blank 166a Fig. 23.

Considering now the ram guide 171, it should be noted that towards the end of the upstroke of reciprocable slide 35 (Fig. 22), said ram guide 171 is moved inwardly by the action of the inwardly curved part of arcuate portion 78 of the guide wall 74 on the guide pin 173, the camming member 178 being thus caused to ride over the corresponding parts of the guide strip 81. The parts are so proportioned that the inward end of the ram guide 171 will be moved into engagement with the inner face 123 of compensating plate 122 to hold the partly formed nail, and also the same nail after being fully formed, in the longitudinal channel 130 by the overlap of the inner ends of the ram guide over the edges of said longitudinal groove 130 as hereinabove explained. The ram guide moves into said engaging position when the guide pin 75

173 reaches the upper extremity 80 of the contoured recess 73.

Referring now more particularly to Fig. 22 it will be understood that when the guide pin 173 reaches the upper end 89 of the contoured recess 73, the camming member 178 will be just above the upper extremity of the camming strip 81 with the lower bevelled edge 180 of the camming member 178 just clear of said upper extremity. Consequently, and owing to the inclination of said lower bevelled edge 180, at the commencement of the downward movement at the reciprocable slide 35, the camming member 178 will be deflected inwardly by engagement of said edge 180 with the upper parts of said camming strip 81, whereby the camming member 178 is positioned to move along the space between the side face 83 of the channel shape member 46 and the straight portion 82 of said camming strip 81, to maintain the ram guide 171 in its fully advanced or inmost position during the whole of the downstroke. In this manner the overlap of the inward end of the ram guide 171 over the longitudinal groove 130 will assist in maintaining the nail in said channel after retraction of the ram and during the effective stroke of the hammer bar 181 to be described hereinbelow.

Shortly after commencement of the downstroke, the actuating pin 175 of the ram 172 will enter the inclined portion 64 of the cam groove 61 (Fig. 4), and travel of said actuating pin 175 along the inclined portion will cause retraction of the ram 172 (Fig. 17) to its outermost position in which it is quite clear of the groove 130 and the therein contained fully formed nail. At the same time, the heading finger 144 will have been retracted from heading position so as to allow the hammer member 181 to descend and engage the head of the nail under the action of the descending upper crosshead 32, the parts being so proportioned that engagement of the hammer bar 181 with the nail head will take place immediately after the heading finger 144 and the ram 172 have been retracted sufficiently to be out of the way.

As the hammer bar 34 descends the hammer member 181 moves downwardly in the groove 130 driving the fully formed nail before it and out through the bottom end of said groove (Fig. 21). If, as previously supposed, a workpiece is positioned underneath the guide block assembly the hammer bar 181 will drive the nail into the workpiece to effect a nailing operation. Said operation is completed when the hammer bar and the two crossheads 32 and 36 reach the bottom of their strokes, which position is illustrated in Figs. 1 and 3 (and 21). The parts will then be in a position to repeat the cycle already described.

While there have been shown and described and pointed out the fundamental novel features of the invention as applied to certain preferred embodiments, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

I claim:

1. A nailmaking and nailing machine adapted to form nails from sheet-metal blanks and to drive the formed nails out under hammer ac-

tion, said machine comprising a guide block, a slide member reciprocably mounted in said guide block, a magazine for nail blanks including an inner end, secured in and carried by the slide member, a longitudinal groove in the slide member, said groove having an open side, feeding means reciprocably mounted in the slide member and having a face movable substantially in a plane common to the inner end of said magazine and the open side of said longitudinal groove, ram means reciprocably mounted in the slide member and positioned perpendicularly to said plane and opposite said open side, hammer means in said groove and reciprocable lengthwise thereof, actuating means for said slide member, actuating means for said hammer means, said hammer actuating means being coupled to said actuating means for the slide member, and actuating means for said feeding means and ram means whereby movement of said slide member in the guide block causes a nail blank to be fed into position in front of the groove, and the ram means to press such blank into the groove to effect a nail forming operation, whereupon said hammer means is caused to drive the formed nail along and out of said groove.

2. A nailmaking and nailing machine adapted to form nails from sheetmetal blanks and to drive the formed nail out under hammer action, said machine comprising a guide block having a central channel, a rear wall and a pair of opposite sides, said channel being parallel to said rear wall and said sides, a feeder slot in said rear wall, a magazine slot extending through one of said sides, an elongated opening in the other side, a slide member mounted in said channel for reciprocation therein, a magazine housing for nail blanks including an inner end secured in and carried by said slide member, said magazine housing extending into said magazine slot, a longitudinal groove in said slide member, said groove having an open side, feeding means reciprocably mounted in the slide member and extending into said feeder slot, cooperating means on said feeding means and in said feeder slot for reciprocating said feeding means, the feeding means having a face movable substantially in a plane common to the inner end of the magazine housing and the open side of the longitudinal groove, a pressing assembly reciprocably mounted in the slide member and extending into said elongated opening, cooperating actuating means in said pressing assembly and in said opening for reciprocating said pressing assembly, hammer means in said groove and reciprocable lengthwise thereof, slide actuating means for said slide member, and actuating means for said hammer means, said hammer actuating means being coupled to said actuating means for the slide member, whereby movement of said slide member in the guide block causes a nail blank to be fed by the feeding means from the inner end of the magazine housing to a position in front of the longitudinal groove and the pressing assembly to press said blank into said groove to effect a nail forming operation, whereupon said hammer means is actuated to drive the formed nail along and out of the groove.

3. A nail making and nailing machine adapted to form nails from sheet-metal blanks and to drive the formed nail out under hammer action, said machine comprising a guide block having a central channel, a rear wall and a pair of opposite sides, said channel being parallel to said wall and sides, a feeder slot in said rear wall, a maga-

zine slot extending through one of said sides, an elongated opening in the other side, slide member mounted in said channel for reciprocation therein, a magazine for nail blanks including an inner end, secured in and carried by the slide member, said magazine housing extending into said magazine slot, a longitudinal groove in said slide member, said groove having an open side, feeding means mounted in the slide member, the feeding means extending into said feeder slot and having a face movable substantially in a plane common to the inner end of said magazine housing and the open side of said groove, cam means in said slot and on said feeding means arranged to cause reciprocation of said feeding means in the slide member, to thereby cause a nail blank to be fed from said inner end into a position in front of said open side of the groove, a pressing assembly reciprocably mounted in the slide member and extending into the elongated opening, said pressing assembly being perpendicular to said common plane, cam means in said opening and on said pressing assembly arranged to reciprocate the pressing assembly in the slide member to cause a blank positioned in front of said groove to be pressed thereinto to be formed into a nail, slide actuating means arranged to cause reciprocation of said slide member in the guide block, and actuating means for said hammer means arranged to cause reciprocation of the hammer means in the slide member in timed relationship with the reciprocation of the slide member.

4. A nailmaking and nailing machine adapted to form nails from sheet-metal blanks and to drive the formed nail out under hammer action, said machine comprising a guide block, a slide member reciprocably mounted in said guide block, a magazine for nail blanks including an inner end, secured in and carried by the slide member, a longitudinal groove in the slide member, said groove having an open side, feeding means reciprocably mounted in the slide member and having a face movable substantially in a plane common to the inner end of said magazine and the open side of said longitudinal groove, heading means reciprocably mounted in the slide member and positioned on the side of the longitudinal groove remote from the open side thereof and perpendicularly with respect to said plane, a guide channel for said heading means in the slide member, said guide channel communicating with the longitudinal groove, ram means reciprocably mounted in the slide member and positioned opposite said open side and in alignment with the heading means, hammer means in said groove and reciprocable lengthwise thereof, slide actuating means for said slide member, actuating means for the hammer means, said hammer actuating means being coupled to the slide actuating means, and actuating means for the feeding means, the heading means and the ram means in said assembly whereby on movement of said slide member in the guide block causes a nail blank to be fed from the inner end of the magazine to a position in front of the longitudinal groove and likewise causes the ram means to be reciprocated to press said blank into said groove in an initial nail-forming operation and said heading member to be reciprocated in the guide channel to form a head on the partly formed nail in a final nail-forming operation, and the hammer means to drive the formed nail along and out of said longitudinal groove.

5. A nailmaking and nailing machine adapted to form nails from sheet metal blanks and to

drive the formed nails out under hammer action, said machine comprising a pedestal including an upper housing flanged at one end, a crosshead chamber secured to the flanges of the upper housing, a guide block assembly detachably secured to the said flanges below the crosshead chamber, and a reciprocable slide member movably mounted in the guide block assembly and having an upper portion extending into the cross-head chamber, a pair of lower slideways and a pair of upper slideways in said cross-head chamber, a lower cross-head mounted to reciprocate in said lower slideways and forming part of the upper portion of the slide member, an upper cross-head mounted to reciprocate in said upper slideway, a main shaft and a counter shaft in said upper housing and extending into the cross-head chamber, a crank member on the main shaft in said cross-head chamber and operatively associated with said upper cross-head, a secondary crank on said countershaft in said cross-head chamber and operatively associated with the lower cross-head, driving means for the main shaft, coupling means between the main shaft and counter-shaft, a magazine for nail blanks including an inner end, secured in and carried by the slide member, a longitudinal groove in the slide member, said groove having an open side, feeding means reciprocably mounted in the slide member and having a face movable substantially in a plane common to said inner end of the magazine and the open side of said groove, ram means reciprocably mounted in said slide member in a position perpendicular to said plane and opposite said open side of the groove, and hammer means depending from the upper cross-head and extending into said groove, and reciprocable therein.

6. In a nail-making and nailing machine, a guide block assembly having a central channel and a slide member reciprocably mounted in said channel, said guide block including a magazine slot, a feeder slot and an elongated opening, said slide member having a front face, an upper end including a cross-head disposed parallel to the front face, a bottom end, a hammer guide channel of elongated cross-section including opposed relatively long sides, said hammer guide channel being disposed between said cross-head and the front face with said long sides perpendicular thereto, said hammer guide channel extending lengthwise from the upper end into said slide member towards the bottom end, a longitudinal groove disposed in said slide member adjacent and parallel to the hammer guide channel and extending from the upper end to the bottom end of the slide member and having an open side communicating with said hammer guide, a hammer bar reciprocably positioned in the hammer guide channel and including a hammer member reciprocably located in the longitudinal groove, a first side, a magazine channel extending through said first side into the slide means and having an inner end flush with the open side of the longitudinal groove, a magazine housing fitting in said magazine channel and extending beyond said first side into said magazine slot, a rear face, a feed bar channel extending from said rear wall into the slide member and having a side flush with the inner end of the magazine channel, a feeder member reciprocably located in the feed bar channel and extending beyond said rear face, into said feeder slot, said feeder member having a face movable substantially in a plane common to the inner end of the magazine

housing and the open side of the longitudinal groove, a second side, opposite the first side, a press channel extending from said second side into the slide member perpendicularly to said common plane, a pressing assembly positioned in said press channel for reciprocation perpendicularly to said common plane in alignment with the open side of the longitudinal groove, and extending beyond said second side into said elongated opening, cooperating camming means in said guide block and on the feeder bar and pressing assembly for causing reciprocation of the feeder bar and pressing assembly in the slide member as said slide member reciprocates in the guide member, slide actuating means for said slide member and actuating means for said hammer bar, said hammer actuating means being coupled to the slide actuating means.

7. In a nail-making and nailing machine, a guide block having a central channel and a slide member reciprocably mounted in said channel, said guide block including a magazine slot, a heading slot, said slide member having a front face, an upper end including a cross-head disposed parallel to the front face, a bottom end, a hammer guide channel of elongated cross-section disposed in widthwise perpendicular relationship to said front face and extending lengthwise into the slide member from the upper end thereof to point intermediate the upper and bottom ends, a longitudinal groove disposed in the slide member adjacent and parallel to the hammer guide channel and extending from the upper end of the slide member to the bottom end thereof, said groove having an open side communicating with said hammer guide channel, a hammer bar reciprocably positioned in the hammer guide channel and including a hammer member reciprocably located in the longitudinal groove, a first side, a magazine channel extending through said first side into the slide member and having an inner end flush with the open side of the longitudinal groove, a magazine housing fitting in said magazine channel and extending beyond said first side into said magazine slot, a heading member guide channel extending from said first side into the slide member and including a transverse groove parallel to the heading member guide channel, said transverse groove being substantially perpendicular to the longitudinal groove and communicating therewith on the side thereof opposite the open side, a heading member slidably mounted in the heading member guide channel for reciprocation therein and including a heading finger slidably fitting in the transverse groove, said heading member extending beyond the first side wall into said heading slot, a rear wall, a feed-bar channel extending from the rear wall into the slide member and having a side flush with the inner end of the magazine channel, a feeder member reciprocably mounted in the feed-bar channel and extending beyond said rear face into said feeder slot, said feeder member having a face movable substantially in a plane common to the inner end of the magazine and the open side of the longitudinal groove, a second side opposite the first side, a press channel extending from the second side into the slide member, a pressing assembly positioned in said press channel in alignment with the open side of the longitudinal groove for reciprocation perpendicularly to said common plane and extending beyond said second side into said elongated opening, cooperating camming means in said guide block and on the

feeder bar, heading member, and pressing assembly, for causing reciprocation of the feeder bar, heading member, and pressing assembly in the slide member, as said slide member reciprocates in the guide block, slide actuating means for said slide member, and actuating means for the hammer bar, said hammer actuating means being coupled to the slide actuating means.

8. In a nail-making and nailing machine of the kind comprising a guide block, a slide member reciprocable in the guide block, magazine means for nail blanks carried by the slide member, blank feeding means reciprocable in said slide member, a longitudinal groove in said slide member having an open side, a pressing assembly comprising a channel shape ram guide mounted for reciprocation in the slide means, a ram member mounted for reciprocation in said channel shape guide, said ram member being in alignment with said longitudinal groove on the open side thereof and of width substantially equal to the width of said groove less twice the thickness of a nail-blank, cam type means on said channel shape guide and in said guide block for causing reciprocation of said channel shape guide in said slide member and cam type actuating means on said ram and in said block for causing reciprocation of said ram in said channel shape guide, as the slide member reciprocates in the guide member.

9. In a nailmaking and nailing machine of the kind comprising a guide means, having a central channel and comprising a rear wall and a pair of opposite sides, a magazine slot in one of said sides, a feeder slot in the rear wall, a press-slot in the other of said sides, said other side including an outside face, a slide member reciprocably mounted in the said central channel, magazine means for nail blanks carried by said slide member and extending into said magazine slot, blank feeding means reciprocably mounted in said slide member and extending into said feeder slot, and a longitudinal groove in said slide member, said groove having an open side, a pressing-assembly including a channel shape guide reciprocably mounted in said slide member, a ram member reciprocably mounted in said channel shape guide, said channel shape guide and said ram extending into said press-slot, a cam groove in one part of the press-slot, an actuating slot in the channel shape guide, an actuating pin on the ram and extending through the actuating slot and into the cam groove, a con-

toured recess including a peripheral guide wall in another part of said press-slot, a guide pin extending into said recess in engagement with said guide wall, a cam strip mounted on the outside face of said other side of the guide member, a camming member extending from said channel shape ram guide and engaging said cam strip, said cam strip having a contour similar to that of the contoured recess, said ram being aligned with the open side of said longitudinal groove and being of a width less than the width of said slot by twice the thickness of a blank, whereby on reciprocation of the slide member in the guide means, the guide pin and the camming member cooperate with the contoured recess and cam strip to move the ram guide towards said longitudinal groove and to retract the same therefrom, and the actuating pin cooperates with the cam groove to cause the ram to enter said longitudinal groove and to be retracted therefrom independently of but in timed relationship with the motion of the ram guide.

10. A nailmaking and nailing machine comprising a guide means having a central channel, 25 a slide member reciprocably mounted in the central channel, a magazine housing for nail blanks mounted in and carried by said slide member, a longitudinal groove having an open side in the slide member, a feeder member reciprocably mounted in said slide member to move a nail-blank from the magazine to a position in which the blank covers said open side of the groove, hammer means reciprocably mounted in the longitudinal groove, a press assembly including a 30 channel shape ram guide mounted for reciprocation in the slide member and a ram mounted for reciprocation in the channel shape guide, the channel shape guide being of length sufficient to be moved into close proximity to said longitudinal groove and said ram being of length to 35 penetrate into said groove, and thereby force a positioned blank into said groove, said ram being of a width equal to the width of the longitudinal groove less twice the thickness of a nail blank 40 whereby said ram guide overlaps the longitudinal groove on either side for the thickness of a blank to hold a pressed blank in said groove, cam type actuating means in said guide block 45 for the press assembly, slide actuating means for actuating said slide member, and actuating means 50 for said hammer means.
